UNITED STATES PATENT OFFICE.

STEVEN KOTELES, OF CLAREMONT, VIRGINIA.

CLASP.

Application filed September 13, 1923. Serial No. 662,432.

To all whom it may concern:

Be it known that I, STEVEN KOTELES, a citizen of Hungary, residing at Claremont, in the county of Surry and State of Virginia, have invented certain new and useful Improvements in Clasps, of which the following is a specification.

This invention relates to new and useful improvements in clasps.

10 This clasp has been specially designed for use in barber shops. Usually, the barber when preparing to cut the hair of a customer, places around the shoulders and body of the customer a cloth which is secured at the nape of the neck by means of a separable fastener or a pin. These pins or separable fasteners often become loosened or undone and hair dropping down the neck of the customer causes great discomfort especially during hot weather.

15 It is therefore, a prime object of this invention to provide a clasp which when used for the above mentioned use, can easily and quickly be adjusted and when once adjusted can be securely locked in position.

20 A still further object of this invention is to provide a device which designed for use in barber shops, is not necessarily limited thereto, but may be used for numerous other purposes such as the hanging of clothing or the like.

25 A still further object of this invention, is to provide a device of the above mentioned character which is compact in structure, durable and strong in use, and one that may be easily and quickly adjusted.

In the drawings,

Figure 1 is a perspective view of my improved clasp,

30 Figure 2 is a side elevational view of the same shown in unlocked position,

Figure 3 is a side elevational view showing the same in a locked position,

35 Figure 4 is an end elevational view showing the clasp in an unlocked position,

Figure 5 is a side elevational view of a slight modification of my invention,

Figure 6 is an end elevational view of Fig. 5, and

40 Figure 7 is a cross sectional view taken on line VII—VII of Fig. 5.

Referring to the drawing, wherein for the purpose of illustration like reference characters are used to designate like parts throughout the several views, the numeral 8 indicates my improved clasp, which has

formed integrally therewith depending side members 9 which are provided with strengthening widths 10. Formed integrally with said clasp 8 is a spring arm 11, the purpose of which will be more fully hereinafter described.

Referring particularly to Figs. 1, 2, 3 and 4, it will be seen that one of the arms 9, has an opening 12, as clearly shown in Fig. 4, formed near the open end thereof. Pivotally mounted in this opening 12 by means of a bracket 13, is a cam 14, which is adapted to engage a spring arm 15 which is riveted to the inside of the depending member 9, as at 16 as clearly shown in Fig. 1. The cam 14 is operated by means of an arm 17 formed integrally therewith.

Mounted in the center of the member 8 and secured by means of riveting as at 18 is a square pin 19 which is provided at its lower extremity with a head 20. Slidably mounted on the pin 19 is a triangular wedge-shaped member 21, which is provided on one of its angles with a plurality of teeth 22. Formed in the apex of the triangular wedge-shaped member 21 is a small square passageway 23 which after a short distance is enlarged to form the passageway 24. Thus the small passageway forms an opening for the pin 19 to pass through while the head 20 of the pin 19 is engaged in the passage 24. The shoulder 25 formed by the meeting of the two passageways 23 and 24 acts as a stop for the shoulder 20 of the pin 19. It will also be seen that on account of the passageways both being square the pin 19 being also square will thereby prevent the turning of the member 21, thereby holding the same in alinement with respect to the sides 9.

Referring to Figs. 1 to 4 inclusive, when anything is desired to be clasped, the material is placed between the sides 9 and 11, the member 21 is then pushed upwardly with the thumb forcing the spring arm 11 toward the side 9 which action firmly clasps the goods. The arm 17 is then pushed upwardly forcing the cam 14 downwardly against the spring arm 15 which will engage one of the saw teeth 22 carried by the member 21 thus locking the same in operative position.

Referring to Figs. 5 and 6 wherein is shown a modification of Figs. 1 to 4 inclusive, there is shown attached to one of the side arms 9 by means of rivets 26 or the like

an outwardly extending arm 27 having an upturned portion 28. The operation of the clasp in Figs. 5 and 6 is substantially the same as before described with the exception that when the member 21 is forced upwardly to clasp the material the member 28 is grasped with the finger and pulled outwardly thus pulling the inwardly turned edge 29 formed on the side member 9 out of engagement with the teeth 22 until the member 21 has been placed in an adjusted position when the member 28 may be released allowing the member 29 to engage with one of the teeth 22.

15 It is to be understood that various changes in the shape, size, and arrangement of parts may be resorted to without departing from the spirit of the invention or the scope of the subjoined claims.

20 Having thus described the invention, I claim:—

1. A clasp having oppositely disposed depending side members, a depending resilient arm formed integral with said clasp, a pin 25 carried by said clasp, slideable clamping means associated with said pin and resilient arm, locking means for said clamping means carried by one of said oppositely disposed depending side members and actuating 30 means associated with said locking means for actuating said locking means.

2. A clasp having oppositely disposed de-

pending side members, a resilient arm carried by said clasp, a pin mounted centrally of said clasp, a triangular wedge-shaped 35 clamping member cooperating with said resilient arm slideable on said pin and means carried by one of said side members for locking said wedge in adjusted position.

3. A clasp having oppositely disposed depending side members, a resilient clamping arm associated with said clasp, a square pin mounted on said clasp, a slideable wedge member mounted on said pin and adapted to engage said resilient clamping arm, teeth 40 formed on one side of said wedge and locking means carried by one of said oppositely disposed depending side members adapted to engage said teeth.

4. A clasp having oppositely disposed depending side members, a resilient clamping arm associated with said clasp, a square pin mounted on said clasp, a slideable wedge member having an opening of large dimension communicating with an opening of 55 small dimension extending longitudinally therethrough mounted on said square pin, teeth formed on one side of said wedge and locking means carried by one of said oppositely disposed depending side members 60 adapted to engage said teeth.

In testimony whereof I affix my signature.

STEVEN KOTELES.
